YARDAGE METER INDICATOR FOR CADDY CARTS

Norman Bruce Williamson, Portland, Oreg.

Application December 7, 1953, Serial No. 27,954

Term of patent 14 years

(Cl. D52—1)

To all whom it may concern:

Be it known that I, Norman Bruce Williamson, a citizen of the United States, residing at Portland, in the county of Multnomah and State of Oregon, have invented a new, original, and ornamental Design for a Yardage Meter Indicator for Caddy Carts, of which the following is a specification, reference being had to the accompanying drawing, forming a part hereof.

Fig. 1 is a perspective view of a yardage meter indicator for caddy carts, showing my new design;

Fig. 2 is a top plan view thereof; and
Fig. 3 is an elevational view thereof.

I claim:

The ornamental design for a yardage meter indicator for caddy carts, as shown.
